UNITED STATES PATENT OFFICE.

FRANCIS NATHANIEL BROWN, JR., OF EL PASO, TEXAS, ASSIGNOR OF ONE-HALF TO
FRANK N. BROWN, SR., OF EL PASO, TEXAS.

CASTING MACHINE.

Application filed April 15, 1925. Serial No. 23,319.

My invention relates to improvements in casting machines, and it consists in the combinations, constructions and arrangements herein described and claimed.

- 5 More particularly described, the present invention is an improvement on the casting machine that is disclosed in Letters Patent of the United States #1,518,630, granted to me December 19, 1924.
- 10 The casting machine which is disclosed in my aforesaid patent is adapted to be used in forming small castings, such as those adapted to be used in dental work, and it affords facilities for subjecting a mass of
- 15 molten metal to pressure to form a metallic object of a desirable shape and at the same time draws air from the space at the bottom of the mold cavity, the means for exerting pressure on the molten metal in the mold
- 20 and the means for drawing air from the bottom of the mold cavity beginning to function at the same time.

An object of the present invention is the provision in a casting machine of the character described of means for exerting pressure on investment material within the mold and for causing suction within the bottom of the mold cavity in combination with means for controlling the operation of said pressure causing means and said suction causing means so that the suction causing means will be operated before the pressure causing means is operated and will continue functioning after the pressure causing means begins to function.

A further object of the invention is the provision in a device of the character described of a novel pneumatic control for applying pressure fluid to a plurality of separate cylinders so that the working stroke of pistons within the cylinders will begin sequentially and will terminate simultaneously.

40 Other objects and advantages of the invention will be apparent from the following description, considered in conjunction with the accompanying drawings, in which

Figure 1 is a view, mainly in front elevation, and partly in vertical section, showing the improved casting machine,

50 Figure 2 is a slightly enlarged fragmentary vertical section through the base portion of the machine and through cooperative members which are disposed beneath the

base and are operable to cause a suction on openings through a rest plate on the base, 55

Figure 3 is a relatively enlarged transverse section through a novel valve which is comprised in the embodiment of the present invention, the view being taken substantially along the line 3—3 of Figure 2. 60

Figure 4 is a vertical section through the machine taken substantially along the line 4—4 of Figure 1,

Figure 5 is a horizontal section taken along the line 5—5 of Figure 1. 65

Figure 6 is a transverse vertical section through a four way cock which is comprised in the embodiment of the invention.

The supporting structure of the improved casting machine comprises a base having a substantially flat top 1 from which a marginal flange 2 depends for supporting the base on a flat surface 3 so that the top 1 will be disposed above the flat surface 3 in spaced parallel relation thereto. The 70 depending marginal flange 2 may be provided at its lower end with any desirable number of spaced outwardly extending attaching ears 4 having vertical openings 5 through which bolts, not shown, or like fastening devices may be projected into the flat surface 3 for securing the base to the supporting surface. A tubular stem 6 is supported on the top 1 of the base and is shown in Figure 4 as being secured to the top 80 of the base by screws 7 so that the stem 6 is in fluid tight contact at its lower end with the top 1 of the base. The standard 6 is secured to the top of the base adjacent to one side of the base, as indicated by the dot and dash lines in Figure 5. The upper end portion of the tubular standard is bent laterally and carries a vertically disposed cylinder 8 which is located directly above an opening in the top 1 of the base. The 85 cylinder 8 is closed at its upper and lower ends by an upper head 10 and a lower head 11 respectively.

The space within the hollow tubular standard 6 is divided longitudinally by a 100 partition 12 into two separate passages 13 and 14 respectively, each of which extends the full length of the tubular standard. A piston 15 is reciprocable in the cylinder 8. The passage 13 communicates with the space 105 within the cylinder 8 through a duct 16 in

the walls of the cylinder 8 above the limit of the upward stroke of the piston. The passage 14 communicates through a duct 17 with the interior of the cylinder 8 at the 5 lower end of the latter and below the limit of the downward stroke of the piston 15. A piston rod 18 extends slidably through a central opening 18^a in the lower head 11 and at its lower end carries a tubular member 19. The function of the tubular or hollow member 19 will presently appear.

The four-way cock has a casing 20 formed to provide a pair of tubular air delivery ports or outlets 21 and 22 respectively, a 15 tubular air inlet port 23 which is located on the casing 20 midway between the air outlets 21 and 22, and an exhaust outlet 24 which also is located on the casing 20 midway between the air delivery outlets 21 and 20 22 and directly opposite the air inlet 23. A plug 25 is mounted to rotate in the casing 20 and is formed with a pair of oppositely curved spaced ducts 26 and 27 respectively, each of which is adapted to establish 25 communication between the inner ends of any two adjacent members 21-24, 24-23, 22-23, and 23-21. An axial stem 28 for the plug 25 (see Fig. 5) extends through an opening in the supporting flange 2 of the 30 base and is provided at its outer end with a handle 29. The handle 29 may be manipulated to rotate the plug 25 to connect the air intake 23 with the delivery outlet 21 and the delivery outlet 22 with the exhaust 24 as 35 shown in Figure 6 or to connect the intake 23 with the delivery outlet 21 and the delivery outlet 22 with the exhaust 24 as shown in Figure 6 or to connect the intake 23 with the delivery outlet 22 and the delivery outlet 21 with the exhaust outlet 24. A 40 supply conduit 30 is connected at one end with the air inlet 23 and extends through an opening in the supporting flange 2 of the base for connection with any suitable source 45 of pressure fluid supply. A conduit 31 is connected at one end to the delivery outlet 22 and has the other end thereof secured in an opening in the top 1 of the base at the lower end of the passage 14. The delivery 50 outlet 21 is connected immediately with the passage 13 by means which will be presently described.

A horizontal suction cylinder 32 has a flat attaching flange 33 on its upper side extending beyond one end of the suction cylinder. This attaching flange 33 is held flatwise against the underside of the portion of the top 1 of the base which surrounds the opening 9 by means of screws 34 which have their heads disposed in countersunk relation to the upper face of the top 1 as shown in Figure 4. A vertical passage 35 through the upper side of the cylinder 32 and through the attaching flange 33 is continuous with the bore 35 of a tubular extension 36 which is supported

in the opening 9 in spaced relation to the wall of the latter. The bore of the tubular extension 36 preferably enlarges from its lower to its upper end as shown in Figure 2. The tubular extension 36 is screw threaded externally for engagement with an internally screw threaded depending tubular projection 37 on a rest plate 38 which thereby will be secured on the top 1 of the base at the upper end of the opening 9. The rest plate 75 38 is adapted to support an investment holding ring 39 of any one of a plurality of different sizes. Apertures 40 in the portion of the rest plate 38 that is disposed at the upper end of the bore of the tubular extension 36 80 establish communication between the space within the investment ring 39 on the rest plate and the passage 36-35 leading to the interior of the cylinder 32 at one end of the latter. A power cylinder 41 has a flat attaching flange 42 on its upper side held flatwise against the downwardly enlarged portion 43 of the top 1 of the base by screws 44 or like fastening devices so that the cylinder 41 will be supported in axial alignment with the cylinder 32 adjacent to the end of the latter which is provided with the suction passage 35. The cylinders 32 and 41 are closed at their adjacent ends by heads having aligned openings through which a rod 45 85 slidably extends. The rod 45 also extends through stuffing boxes 46 and 47 which respectively are provided at the end of the cylinder 41 and the end of the cylinder 32 which are adjacent each other. The rod 45 is connected at one end to a piston 48 which is reciprocable in the cylinder 41 and is connected at its other end to the piston 49 which is reciprocable in the cylinder 32. 90

The cylinder 41 is closed at its other end by an imperforate head 50. The cylinder 32 is closed at the end thereof that is remote from the cylinder 41 by a head 51 formed with an outwardly extending axial boss 52. A central opening 53 extending through the head 51 of the boss 52 is enlarged at its inner end as indicated at 54 in Figure 2 of the drawing. The boss 52 is threaded externally for engagement with the threaded wall of a counterbore 55 at one end of the central bore 56 of a tubular valve casing 57. The tubular valve casing 57 is provided also with a counterbore 58 at its other end and the bore 56 is enlarged to provide a chamber 59 midway between the counterbores 55 and 58. 100 The bore 56 is enlarged and beveled at its juncture with the counterbore 55 to provide a tapering seat 60 for a beveled valve 61. The valve 61 is movable in the counterbore 55 between the seat 60 and the outer end of the boss 52 and has an axial guide stem 62 extending in the bore 56 from the counterbore 55 into the chamber 59. The bore 56 also is enlarged and beveled at its juncture with the counterbore 58 to provide a taper- 105 110 115 120 125 130

ing valve seat 63 for a beveled valve 64. The valve 64 is provided at its inner end with an axial guide stem 65 extending in the bore 56 and the chamber 69 against the outer end of the stem 62, the length of the stems 62 and 65 combined being greater than the distance between the valve seats 60 and 63. The counterbore 58 is closed at its outer end by a screw plug 66 formed with a central recess 67 in its inner face. An expansion spring 68 has the outer end portion thereof received in the recess 67 and bears at its inner end against the valve 64 in encircling relation to a retaining pin 69 which extends axially from the outer face of the valve 64. The spring 68 holds the valve 64 against its seat and therefore also tends to hold the valve 61 away from its seat. The chamber 58 is provided with a lateral part 70 with which one end of a tubular conduit 71 is connected. The chamber 59 also is provided with a lateral port with which a tubular conduit 72 is connected. The chamber 55 is provided with a lateral port 74 open to the atmosphere. The valve stem 62 is provided with grooves 75 extending longitudinally thereof from the valve 51 to the free end of the stem 62 and constituting air passages. The stem 65 is provided with similar grooves, indicated at 76.

The power cylinder 41 is provided adjacent to the end thereof that is proximate to the cylinder 32 with a lateral port with which a tubular conduit 77 is connected. The tubular conduit 77 is connected at its other end to the conduit 31. The power cylinder 41 also has a port adjacent to its other end with which a tubular conduit 78 is connected. The tubular conduits 71 and 78 are branches of a conduit 79 which is connected to the tubular delivery outlet 22 of the four way cock.

A lid or cover 80 for closing the upper end of the investment holding ring 39 is carried at the lower end of the tubular member 19 and is movable vertically with the rod 18 and therefore with the piston 15 to and from position to rest on the investment holding ring 39. When the piston 15 is at the lower end of its stroke in the cylinder 8, the cover 80 will be clamped tightly against the upper end of the investment holding ring 39 and will close the latter. When the piston 15 is at the upper end of its stroke as shown in Figure 4, the cap or cover 80 will have been lifted from the investment holding ring 39 and will be positioned above the latter. The cap or cover 80 is provided with a central opening 81 for establishing communication between the interior of the member 19 and the space within the investment holding ring 39 when the cap or cover 80 is in position on the investment holding ring. Flow of pressure fluid from the passage 13 to the space within the member 19, which is closed at its upper end, may take place through any suitable pressure regulating device 82 and a flexible tubular conduit 83 which connects the pressure regulating device 82 with the space within the member 19. It of course is desirable that means be provided within the tubular member 19 for preventing flow of pressure fluid from the tubular conduit 83 until the cap or cover 80 shall have been lowered onto the investment holding ring 39. In my aforesaid prior patent I have disclosed a novel means for accomplishing this result but since the same per se forms no part of the present invention, I have not illustrated the same in the accompanying drawings. However, it is to be understood that I may make use of the specific means that is disclosed in my aforesaid prior patent to control the flow of pressure fluid through the casing member 19 so that no pressure fluid will pass through the opening 81 of the cap or lid 80 until the latter has been lowered into position on the investment holding ring 39.

From the foregoing description of the various parts of the device, the operation thereof may be readily understood. The handle 29 is manipulated to connect the pressure fluid intake 23 through one of the ducts in the plug 25 of the four-way cock with the delivery outlet 21 and therefore with the conduit 79. At this time, the delivery outlet 22 and therefore the conduit 31 would be connected with the exhaust outlet or port 24 through the other duct in the plug 25 of the four way cock. Pressure fluid will flow through the conduit 79 and the branch conduits 78 and 71 into the chamber 58 at the outer end of the valve casing 57 and into the outer end of the power cylinder 41. The power cylinder 41 is of greater area in cross section than the chamber 58 and the pressure within the outer end of the power cylinder 41, having caused movement of the pistons 48 and 49 in the cylinders 41 and 32 respectively until a pusher rod 84 on the piston 49 has been projected through the opening 53 in the head 51 against the valve 61, will cause the valves 61 and 64 to be moved as a unit against the combined action of the spring 68 and fluid pressure within the chamber 58 until the valve 64 is moved from its seat and the valve 61 is moved against its seat. However, suction resulting from the movement of the piston 49 in the cylinder 32 will commence at the beginning of the stroke of the piston 49 while the valve 64 will not be moved from its seat until the suction stroke of the piston 49 has been nearly completed. As soon as the valve 64 is moved from its seat, pressure fluid will flow past the valve 64 along the grooves 76 in the bore into the chamber 59 and thence through the conduit 73 into the

passage 13. From the passage 13, pressure fluid will pass into the upper end of the cylinder 8 and will cause the piston 15 to move downward in the cylinder 8, thereby causing the cap or cover 80 to be lowered to position on the investment holding ring 39. At the same time, pressure fluid passes from the passage 13 to the pressure regulating device 82 and conduit 83 into the tubular member 19 and after the cover 80 has been lowered to position on the investment holding ring 89, pressure fluid passes from the tubular member 19 at the opening 81 of the cover 80 into the upper part of the investment holding ring for the purpose of exerting pressure on the investment material in the investment holding ring so that a compact casting of a desired shape may be formed. It will be manifest that air from the mold cavity will have been withdrawn from the mold cavity as a result of the suction on the apertures 40 before pressure is exerted on the investment material at the upper end of the investment holding ring and that the suction on the apertures 40 and therefore on the lower portion or bottom of the mold cavity will continue while pressure is being applied on the investment material at the upper end of the investment holding ring after the cover 80 has been lowered to position as a result of the operation just described. When the casting has been formed and it is desired to raise the cover 80 from the investment holding ring, the handle of the fourway cock is manipulated to connect the tubular plug 21 with the exhaust port 24 and to connect the tubular port 22 with the intake port 23.

Pressure fluid then will flow through the conduit 31 into the passage 14 and thence to the lower part of the cylinder 8. The piston 15 will be moved upward in the cylinder 8, thereby causing the cover 80 to be lifted from the investment holding ring. At the same time, pressure fluid will pass through the conduit 77 to the inner end of the cylinder 41 and the piston 48 will be moved in the cylinder 41 toward the head 50 or in other words away from the cylinder 32. As pointed out in my aforesaid prior patent, any suitable sealing substance may be placed in the passage 35 and within the space in the tubular extension 36 for the purpose of preventing return movement of air to the apertures 40 in the investment holding ring during the return stroke of the piston 49 in the suction cylinder. While the suction stroke of the piston 49 takes place, the exhaust from the outer end of the cylinder 32 and from the chamber 55 will be through the port 74. As soon as the piston 49 starts on its return stroke, the piston rod 84 begins to move away from position to hold the valve 61 closed and the valve 61 starts to move toward open position or away from its

seat and the valve 64 starts to move toward its seat. During the early part of the return stroke of the piston 49, the exhaust from the upper part of the cylinder 8, from the passage 13, conduit 73 and chamber 59 is principally through the bore 56, chamber 58, conduit 71, conduit 79 and exhaust port 24 of the four way cock. However, as soon as the valve 61 moves away from its seat, some exhaust will take place from the chamber 59 and the hereinbefore mentioned parts with which the chamber 59 is in communication through the bore 56, chamber 55 and exhaust port 74. After the piston 49 has moved on its return stroke a distance sufficient to permit the valve 64 to be moved by the spring 68 against its seat, any pressure fluid remaining in the chamber 59 and the parts in communication with the chamber 59 may escape through the bore 56, chamber 55 and port 74.

I claim:

1. In a casting machine of the character described, a cover for one end of an investment holding ring, said cover having an opening through which pressure fluid may enter said investment holding ring when the cover is in position to close said one end of the investment holding ring, a pneumatic operated plunger for moving said cover to and from position to close said investment holding ring at its said one end; pneumatic means associated with the investment holding ring at its other end for causing a suction within said investment ring at its second named end, and means for controlling the flow of pressure fluid through said suction causing device means and through said cover operating piston so that the suction causing device means will be operated in advance of and continue during the movement of said piston to position to move said cover against the first named end of the investment holding ring.

2. In a casting machine of the character described, a suction cylinder having a suction passage adjacent one end thereof, means for supporting an investment holding ring so that said suction passage will be in communication with the space within the investment holding ring at one end of the latter, a piston within said suction cylinder, a pneumatic cylinder in alignment with said suction cylinder, a piston within said pneumatic cylinder, a piston rod connected to the piston of the pneumatic cylinder with the piston of the suction cylinder, a cover for the second end of said investment holding ring, said cover having an opening through which pressure fluid may enter the investment holding ring, an additional pneumatic cylinder, a plunger in the last named pneumatic cylinder connected with said cover for moving the latter to and from position to close the second named end of the invest-

ment holding ring, and means for supplying pressure fluid to said first named pneumatic cylinder and to said last named pneumatic cylinder, said pressure fluid supply means acting to move the piston in said suction cylinder in the direction required to cause suction within the first named end of

the investment holding ring in advance of the movement of the piston in the last named pneumatic cylinder in the direction required to move said cover to position to close said investment holding ring at its second named end. 10

FRANCIS NATHANIEL BROWN, Jr.
